CLAIM

The ornamental design for the tongue scraper, as shown and described.

DESCRIPTION

FIG. 1 is a perspective view of a tongue scraper showing my new design;

FIG. 2 is a perspective view as seen from the end opposite that shown in FIG. 1;

FIG. 3 is a top plan view, the bottom view being identical;

FIG. 4 is a side elevational view, the side not shown being a mirror image of the side shown;

FIG. 5 is an end elevational view; and,

FIG. 6 is an end elevational view opposite that shown in FIG. 5.
